LAPEL

Hilary W. Lucas and David Zimmerman,
Cleveland, Ohio; said Lucas assignor to said
Zimmerman

Application November 18, 1942, Serial No. 465,951

2 Claims.

(Cl. 2—93)

Our invention is an improvement in wearing apparel and relates more particularly to lapel attachments for coats.

It is one of the objects of our invention to provide a lapel which can readily and removably be applied over the lapel portion of a coat whereby the coat may be given the appearance of a tuxedo or dinner coat.

Another object of the invention is to provide a lapel attachment which is simple of construction and inexpensive to manufacture and which is provided with means whereby it may be removably secured over the lapel of the coat in such fashion that it will lie flat and present a neat appearance.

A further object of the invention is to provide a lapel attachment having a button hole formed therein which is positioned to underlie the adjacent button hole in the coat and in a direction intersecting the direction of the coat button hole to thereby insure proper alignment of the attachment on the coat when the coat is buttoned.

A further object of the invention consists in providing a lapel attachment having a button hole extending in a lengthwise direction with respect to the lapel and adapted to lie in a direction intersecting the direction of the customary button hole in the coat in such fashion that it will enable the lapel to be attached to different coats in which the coat button and corresponding button hole is disposed in different vertical positions with respect to the bottom edge of the coat.

Other objects and advantages of our invention will become more apparent as the following description of an embodiment thereof progresses, reference being made to the accompanying drawing in which like reference characters are employed to designate like parts throughout the same.

In the drawing:

Figure 1 is a front elevation of an embodiment of our invention.

Figure 2 is a rear elevation of the same.

Figure 3 is a transverse section taken on line 3—3 of Figure 2, and,

Figure 4 is a front elevation of the illustrated embodiment of the invention as applied in use.

This invention is an improvement upon the invention disclosed in a co-pending application, Serial No. 421,601, filed December 4, 1941, by David Zimmerman, one of the applicants herein. The present invention possesses several novel advantages over that disclosed in the co-pending

application as will be pointed out as the description progresses.

The embodiment of the lapel attachment as shown herein comprises an outer face 1 of silk or other suitable cloth for the purpose intended, and a lining 2. Both the lapel and the lining may be cut from the same pattern and are secured together along their outer edges by stitching as at 3 the edges of the cloth along the seam being disposed inwardly between the outer face and the lining to present a well-finished appearance.

While only one lapel is shown in the accompanying illustrations it is, of course, intended that the lapels be furnished in pairs constituting a right and left lapel attachment. In order that the lapel attachments may receive the respective coat lapels, the lining 2 is cut away at 4 as indicated in Figure 2 to provide an opening into which the lapel of the coat may be inserted between the outer face 1 and the lining 2. A flap is formed of the lining material and is indicated at 5. The flap 5 overlies the lapel receiving opening and the edge of the lining which is indicated by the dotted line 4 in Figure 2. When the lapel attachment is assembled over the coat lapel the flap 5 will overlie the under surface of the coat lapel and while we have shown no fastening means for directly attaching the flap to the underside of the coat lapel, the same may be used if desired. It is found in practice, however, that the flap will lie flat under the lapel without the use of fastening devices.

One of the important advantages of our invention resides in the fact that the lapel attachment is provided with an elongated slit near its lower end extending in a direction substantially longitudinal of the lapel and forming in effect a button hole 6. The location of this button hole is such that when the attachment is applied to a coat lapel as in Figure 4 the button hole 6 will be disposed adjacent the inner surface of the coat near the front edge thereof and will be completely hidden from view. It will also be noted that the button hole 6 is so located that its longitudinal axis lies in a plane intersecting the plane of the longitudinal axis of the coat button hole 7. In this manner both vertical and horizontal adjustment of the overlying front coat edges, and the lapel attachment is assured, thus enabling the coat button 8 to pass through the angularly disposed button holes 6 and 7 without disturbing the natural conformity of the attachment to the coat lapel to which it is attached. The location of the button 8 and the correspond-

ing button hole 7 of the coat is not necessarily the same in every coat although its location may be approximate. It will, therefore, readily be understood that in applying a lapel attachment such as is provided by our invention for interchangeable use with several coats, we have provided means by which the lapel attachment is caused to enclose the coat lapel and to lie unwrinkled regardless of the position of the button hole and button 7 and 8 respectively of the coat. For instance, if the said button and button hole were located either slightly above or slightly below the position indicated in Figure 4 the substantial vertical disposition of the slit or button hole 6 still permits passage of the button 8 through the button holes 6 and 7 without disturbing the position of the lower end of the lapel attachment, thereby insuring a neat appearance.

The inner edges of the lapel attachment may be furnished with fastening means 9 for removably securing the same to the inner surfaces of the coat.

We claim:

1. A lapel attachment for coats, comprising a

facing, a lining member underlying the facing and secured thereto along its periphery, said lining having an opening for receiving a coat lapel between it and the facing, said facing and lining having an elongated slit or opening disposed substantially longitudinally of the attachment and adapted to lie behind and in a direction intersecting the button hole of a coat to which the attachment is applied.

2. The combination with a coat having lapels and a button hole formed in one of its front overlapping portions, of a lapel attachment comprising a facing and a lining seamed together along their edges, said lining having an opening to receive one of the lapels of the coat between the facing and lining, said lapel attachment having an elongated lower portion adapted to lie behind said one front portion of the coat and having a button hole formed therein, said button hole lying immediately behind the coat button hole and in a direction intersecting the direction of the latter.

HILARY W. LUCAS.

DAVID ZIMMERMAN.
